EXPANSION VALVE

Roy W. Johnson, Milwaukee, Wis.

Application March 21, 1938, Serial No. 197,105

5 Claims. (Cl. 236—92)

This invention relates to an improvement in thermostatic expansion valves combined with a vapor compression refrigerator machine.

One of the objects of the present invention is to provide a valve of this character which is so compactly and closely organized as to require a minimum number of parts and hence be small in size and yet of rugged construction and highly efficient and reliable, though flexible, in operation.

Another object of the invention is to provide a thermostatic expansion valve which is supersensitive in that a diaphragm of comparatively large area operates directly on a small needle valve so mounted and controlled as to eliminate practically all friction. The valve is of the cartridge type and is so constructed and organized as to be self-aligning and exercise a very close regulating function and yet is readily removable to provide, if ever necessary, for replacement or change of orifice size. Because of its supersensitive character the valve holds super-heat within very narrow limits. Provision is made however, for an adjustable super-heat range. For example, the particular valve structure disclosed herein has an adjustable super-heat range between 0 and 35 degrees Fahrenheit.

In order to have the desirable small size and simplicity of structure and also obtain efficient operating characteristics, a charging refrigerant such as methyl chloride is employed in the power element having a vapor pressure curve lying below that of the system refrigerant such as freon and a loading spring is combined with the diaphragm of the power element in such manner as to make it possible to obtain an equilibrium. The loading spring and the adjustable spring for increasing or decreasing the super-heat are concentrically disposed in the outlet chamber of the valve as a further measure to render the structure small and compact.

The outlet chamber into which the refrigerant directly flows from the orifice has one of its walls constituted by the diaphragm of the power element. The organization is such that when the valve opens, the refrigerant in the outlet chambers exerts a cooling effect through the diaphragm on the charging refrigerant of the power element located on the opposite side of the diaphragm resulting in an instantaneous closing movement of the valve. Hence the valve is self-modulating or dampening in action.

While the area of the diaphragm is large in relation to the metering valve proper, the valve as a whole, diaphragm included, is small, and

this makes it practical to provide a pressure chamber on the power side of the diaphragm of small volume. As usual this pressure chamber connects through a capillary tube with a bulb clamped to the suction line or some suitable part of the evaporator. The small volume of the pressure chamber of the power element makes it practical to employ a bulb of small size and yet having a volume greater than the combined volume of the pressure chamber and the capillary tube. For example, if the combined volume of the pressure chamber and capillary tube is 8 cubic centimeters then a bulb is employed which has a volume of 8.3 cubic centimeters. With this relationship between the pressure chamber, capillary tube, and bulb of the power element, the power element may be so charged with refrigerant that the refrigerant will always have the surface from which vaporization occurs disposed within the confines of the bulb. This has the important advantage of insuring that the bulb has control at all times and under all conditions. The bulb will retain control even though the expansion valve is encased in ice. Hence the valve body can be placed in an ambient temperature higher or lower than the bulb temperature.

The invention provides a thermostatic expansion valve which maintains a constant super-heat over a wide range of evaporator temperatures and which permits operation at low super-heat at normal operating pressures without flooding back on high evaporator temperatures. There is not only assurance against flooding back of the liquid at the starting cycle but the power needed in the compressor motor, when the evaporator temperature is high, is limited.

Other objects and advantages reside in certain novel features of the construction, arrangement and combination of parts which will be hereinafter more fully described and particularly pointed out in the appended claims, reference being had to the accompanying drawing forming a part of this specification, and in which:

Figure 1 is a view partly in central vertical section and partly in side elevation showing a thermostatic expansion valve embodying the present invention together with its capillary tube and bulb;

Figure 2 is a view in perspective of the parts shown in Figure 1; and

Figure 3 is a diagrammatic view in elevation illustrating the application of the expansion valve, its capillary tube and bulb to a refrigerating system.

Referring to the drawing, the expansion valve

is designated generally by the reference character V, the capillary tube at C, and its cooperating bulb at B. As usual, the expansion valve V is incorporated in the liquid refrigerant supply line L leading to the cooling or evaporator coil E and the bulb B is clamped to the suction line S leading from the evaporator coil E to the motor driven compressor M.

The expansion valve V comprises a valve body 5 provided with an inlet 6 equipped with a strainer 7 and also provided with an outlet 8. A passageway 9 leads from the inlet 6 into the opening or port of a ported partition designated at 10. The partition 10 has an integral upwardly 15 extending sleeve 11 provided at its upper end with an inturned flange 12. A unitary valve assembly or cartridge type valve designated generally at 13 is inserted in the sleeve 11 and regulates and meters the flow of liquid refrigerant through the 20 ported partition and into an outlet chamber 14 in open communication with the outlet 8.

One of the walls of the outlet chamber is constituted by the diaphragm 15 of the valve V, the periphery of the diaphragm being clamped 25 between an outwardly extending annular flange 16 integral with the upper end of the valve body and the periphery of a head 17 which is mechanically interlocked with and sealed to the flange 16. The head and the diaphragm 15 define between them the pressure chamber 18 of the power element of the valve, which power element is constituted of this pressure chamber and its diaphragm, the capillary tube C and bulb B.

35 The cartridge type valve 13 comprises a valve cage 20 which is threadedly interconnected with the sleeve 11, a valve seat 21 threadedly interconnected with the cage 20, a needle valve 22 which is floated in the cage 20 and co-acts with 40 the seat 21, and a spring 23 which is interposed between the lower end of the needle valve and the bottom of the cage and which biases the needle valve to closed position, that is, into engagement with its seat. The lower portion of 45 the cage 20 is of reduced external diameter and has passages 24 extending therethrough to afford communication between that portion of the interior of the ported partition which communicates with the passage 9 and the interior of the 50 cage and of the valve seat. The valve 22, except for its lower end portion, is smaller than the opening through the cage and valve seat so that the liquid refrigerant can flow around the valve to the port or orifice in the valve seat. The lower 55 end of the valve 22 has guiding engagement with the lower portion of the wall of the cage, as indicated at 25.

This unitary valve assembly may be inserted in the sleeve and removed therefrom through 60 the port of the partition and through an opening in the bottom of the valve body.

In the assembly, the valve cage 20 is turned up in the sleeve 11 until the shouldered upper end of the valve seat 21 firmly abuts the inturned flange 65 12 of the sleeve 11. After the valve assembly has been inserted, the inlet side of the valve is sealed off by means of a flanged cap nut 26 threaded into the lower end of the port of the partition and having hermetic sealing engagement therewith.

The diaphragm 15 directly operates the valve 22 and for this purpose it is provided at its center with a buffer plate arrangement 27 securely interconnected mechanically and intersealed 70 with the diaphragm and having a depending pin 75

28 which engages the point of the valve 22. A reticulated or perforated cap-like guide 28' is carried by the buffer plate 27 and telescopes over the upper end of the sleeve 11.

As will be understood from the drawing, the 5 invention proposes a diaphragm of comparatively large area operating directly on a small needle valve which is so constructed and mounted as to be practically frictionless. These features of themselves tend to make the expansion 10 valve super-sensitive and enable it to hold super-heat within very narrow limits.

In order to obtain the desired operating characteristics and yet avoid the use of differential bellow or differential diaphragm arrangements 15 and to have the desirable small size and simplicity of structure, the present invention proposes to employ a charging refrigerant in the power element having a vapor pressure curve lying below that of the system refrigerant and 20 combine a loading spring 29 with the diaphragm in such manner as to make it possible to obtain an equilibrium. The loading spring 29 applies a constant force to the diaphragm 15 tending to flex the same in the same direction as pressure 25 in the chamber 18. The force which the spring applies to the diaphragm is determined by reference to the two vapor pressure curves and the effective area of the diaphragm. In the construction illustrated the loading spring 29 is disposed in the outlet chamber 14 and has its upper end abutting a fixed abutment plate 30 secured to the valve body by means of a split snap ring 31. The spring 29 encircles a connecting shell 32 and has its lower end abutting an outwardly 35 directed flange 33 provided at the lower end of this connecting shell. The connecting shell, while open at its lower end, has an upper end plate 34 which is secured to the diaphragm by being clamped to the parts that make up the 40 buffer plate 27.

While the area of the diaphragm 15 is large in relation to the size of the valve 22, the expansion valve as a whole, including the diaphragm 15, is small and consequently the pressure chamber 18 is of small volume. The small volume of the pressure chamber makes it practical to employ a small bulb B, which, nevertheless, has a capacity or volume greater than the combined volume of the pressure chamber 50 18 and the capillary tube C. With this relation between the pressure chamber 18, capillary tube C, and bulb B of the power element, the power element may be and is, so charged with refrigerant or volatile liquid that the refrigerant will 55 always have the exposed surface thereof from which evaporation occurs located or disposed within the confines of the bulb B. This has the important advantage of insuring that the bulb B is in control at all times and under all conditions and this even though the expansion valve V is encased in ice. In other words, the valve body may be placed in an ambient temperature lower or higher than the bulb temperature without adversely affecting the operation. 65

Provision is made for adjusting the super-heat range of the valve and resides in the provision of an adjustable spring 35 which engages the diaphragm and opposes or bucks the action of the pressure in the pressure chamber 18. In the valve 70 construction here shown this spring 35 is located in concentric relation to the loading spring 29 and preferably is disposed within the connecting shell 32 and in surrounding relation to the sleeve 11. The upper end of the spring 35 bears against 75

the end plate of the connecting shell 32 and consequently is directly mechanically related with the diaphragm 15. The lower end of the spring 35 bears on an adjustable abutment ring 36 which is shiftable along sleeve 11 under the control of suitable means. Preferably the means for adjusting the abutment 36 and consequently varying the force of the spring 35 and increasing or decreasing the super-heat includes a plurality of push pins 37 which extend through and are slidably interfitted with openings 38 provided in the ported partition around the outside of the sleeve 11. Any suitable number of these push pins may be provided, although usually three are sufficient. The upper ends of the push pins engage the underside of the adjustable abutment 36. The lower ends of these pins rest on a shiftable plate 39 which is centrally apertured and swivelly interconnected with an adjusting screw 40, the center aperture of the plate fitting over a reduced extension of the screw and the portion of the underside of the plate which surrounds the center opening engaging a shoulder on the screw. The screw 40 has its threaded portion 41 threadedly engaged with the internally threaded portion of a hexagon nut 42 which is threaded into the lower end of an opening 43 provided in the valve body below the ported partition 10. The shank of the screw works through packing 44 compressed by a follower 45 threadedly engaged with a gland 46 provided on the nut, and in all adjustments of the screw the lower end of its shank projects below the follower 45. The lower end portion of the screw may be provided with flats 47 to facilitate its manipulation by a suitable tool. A cap or bonnet 48 is threadedly interconnected with the gland 46 and provides an enclosure for the screw. By removing the cap or bonnet 48 and turning the screw a super-heat may be increased or decreased as desired. The valve shown has an adjustable super-heat range between 0 and 35 degrees Fahrenheit. By removing the hexagon nut 42 and the closure nut 26, the valve assembly may be readily removed and the valve seat replaced or changed if desired.

An expansion valve of this character is very simple in its operation. Warming of the bulb B caused by increased load on the evaporator increases the pressure in the power element of the expansion valve and in the pressure chamber 18, thereby flexing the diaphragm 15 downwardly and having the needle valve to open position. The resulting increased flow of the refrigerant cools the refrigerant coil E and the expansion valve bulb B, thereby decreasing the pressure in the pressure chamber 18 and allowing the spring 33 to close the valve 22.

As previously stated, the diaphragm 15 constitutes a wall of the outlet chamber into which the refrigerant directly flows as it issues from the orifice of the valve seat. The refrigerant in the outlet chamber is in contact with the diaphragm and has a cooling effect on the refrigerant or volatile liquid in the pressure chamber 18 on the opposite side of the diaphragm so that as the valve 22 opens, the pressure in the chamber 18 is momentarily reduced and a closing movement is imparted to the valve 22 thereby setting up a self-modulation or dampening action of the valve which improves the operation of the system. The valve maintains a constant super-heat over a wide range of evaporator temperatures. The power element is so constituted as to obtain an absolute shut-off of the valve on

the off cycle. This permits operation of the lower super-heat at normal operating pressures without flooding back on high evaporator temperatures. The use of a single diaphragm of large area together with the small amount of friction present in the valve 22 results in a very close valve regulating action. 5

While I have shown and described one construction in which the invention may be advantageously embodied, it is to be understood that 10 the construction shown has been selected merely for the purpose of illustration or example and that various changes in the size, shape and arrangement of the parts may be made without departing from the spirit of the invention or the 15 scope of the subjoined claims.

The invention claimed is:

1. A thermostatic expansion valve of the character described comprising a valve body having an inlet and an outlet, a valve seat interposed 20 between said inlet and said outlet, a valve cooperable with said seat to regulate flow therethrough, said valve body having an outlet chamber on one side of said seat, a diaphragm interrelated with the valve body and interconnected 25 with the valve, means co-acting with the diaphragm to define a pressure chamber, a capillary tube and bulb connected to the pressure chamber and co-acting therewith to provide the power element of the valve, said power element containing 30 a charging refrigerant adapted to operate in vapor phase under same conditions of state as the system refrigerant and having a vapor pressure curve lying below that of the system refrigerant, a loading spring disposed in said outlet chamber and co-acting with the diaphragm to supplement the action of pressure in said pressure chamber, and an adjustable spring also disposed in the outlet chamber and engaged with the diaphragm to oppose the action of pressure in 35 said pressure chamber and thereby control the super-heat in the system with which the valve is associated. 40

2. An expansion valve of the character described comprising a valve body having an inlet 45 and an outlet, a ported partition interposed between said inlet and said outlet and having a valve seat, a valve cooperable with said seat to regulate flow therethrough, said valve body having an outlet chamber on one side of said valve 50 seat, a diaphragm interrelated with the valve body and interconnected with the valve, means co-acting with the diaphragm to define a pressure chamber, a capillary tube and bulb connected to the pressure chamber and co-acting therewith 55 to provide the power element of the valve, said power element containing a charging refrigerant having a vapor pressure curve lying below that of the system refrigerant, a loading spring disposed in said outlet chamber and co-acting with 60 the diaphragm to supplement the action of pressure in said pressure chamber, an adjustable spring disposed in the outlet chamber in concentric relation to the loading spring and engaged with the diaphragm to oppose the action of pressure in said pressure chamber and thereby control the super-heat in the system with which the valve is associated, and means for varying the compression of the adjustable spring and comprising a shiftable abutment therefor, push pins 65 engaged with said abutment, said ported partition having a plurality of openings through which the push pins are slidably fitted, and screw means operable from the exterior of the valve body for shifting said push pins. 70 75

3. A thermostatic expansion valve of the character described comprising a valve body having an inlet and an outlet, a ported partition interposed between the inlet and the outlet and provided with a valve seat, said valve body having an outlet chamber on one side of the valve seat and having an opening on the other side thereof, a valve cooperable with the valve seat for regulating flow therethrough, a diaphragm interconnected with the valve body, means co-acting with the diaphragm to define a pressure chamber, a capillary tube and bulb connected to the pressure chamber and containing a volatile fluid expandible and contractible under the influence of variations in temperature to which the bulb is subjected, means operatively interconnecting the diaphragm and the valve, a spring disposed in the outlet chamber and co-acting with the diaphragm to oppose the action of pressure in the pressure chamber and thereby vary the superheat, an adjustable abutment disposed in the outlet chamber and engaged with said spring, a removable nut for said opening, a screw threadedly engaged with the nut and having one end located in the opening of the valve body and having the other end projecting exteriorly of the nut, a plate in the opening of the valve body engaged with the screw and shifted thereby, and push pins interconnecting the plate and the abutment, the ported partition having openings through which the push pins extend.

4. An expansion valve of the character described comprising a valve body having an inlet and an outlet, a ported partition interposed between the inlet and the outlet and having a valve seat, a valve cooperable with said seat for regulating flow therethrough, said valve having an outlet chamber on the outlet side of said seat, a diaphragm of good thermal-conductivity interconnected with the valve body and forming a wall of said outlet chamber, means directly connecting the diaphragm and the valve, means co-acting with the diaphragm to define a pressure

chamber, a capillary tube and bulb connected to the pressure chamber and co-acting therewith to provide the power element of the valve, said power element containing a charging refrigerant adapted to operate in vapor phase under same conditions of state as the system refrigerant and having a vapor pressure curve lying below that of the system refrigerant, a loading spring disposed in said outlet chamber and co-acting with the diaphragm to supplement the action of pressure in said pressure chamber, an adjustable spring also disposed in the outlet chamber and co-acting with the diaphragm to oppose the action of the pressure in the pressure chamber, and means co-acting with the adjusting spring to vary the force which it applies to the diaphragm and thereby vary the super-heat in the system with which the valve is associated.

5. A thermostatic expansion valve of the character described comprising a valve body having an inlet and an outlet, a valve seat interposed between said inlet and said outlet, a valve cooperable with said seat to regulate flow therethrough, a diaphragm interrelated with the valve body and interconnected with the valve, means co-acting with the diaphragm to provide the power element of the expansion valve, said power element containing a charging refrigerant adapted to operate in vapor phase under same conditions of state as the system refrigerant and having a vapor pressure curve lying below that of the system refrigerant, a loading spring disposed in said outlet chamber and co-acting with the diaphragm to supplement the action of pressure in said pressure chamber, and an adjustable spring disposed in the outlet chamber in concentric relation to the loading spring and engaged with the diaphragm to oppose the action of pressure in said pressure chamber, and thereby control the super-heat in the system with which the valve is associated.

ROY W. JOHNSON.
